ABSTRACT OF THE DISCLOSURE

An electromagnetic device defining a closed magnetic circuit includes a shell-type laminated magnetic core having a centre limb carrying a winding and having a pair of pole pieces whose opposing surfaces are spaced apart from one another. The winding is energisable to cause the pole pieces to assume opposite polarities. A tapered elongate magnetic member is disposed between the pole pieces with its major axis extending transversely of the center limb of the core to provide two air gaps one on each side of the major axis of the member. The member is mounted on the core and movable along its major axis between stop positions to vary the reluctance of the magnetic circuit. The opposing surfaces of the pole pieces and the member have the same shape and the same angle of taper so that, for any position to which the member is moved, each air gap is of constant length over the whole of the opposing surface of the respective pole pieces.

This invention relates to electromagnetic devices, and particularly relates to means for varying the reluctance of a magnetic circuit defined by such a device.

From one aspect, the present invention consists in an electromagnetic device comprising a magnetic core defining a closed magnetic circuit and having opposing poles spaced apart from one another with an air gap therebetween, and a magnetic member mounted in said gap and relatively movable between the poles, the surfaces of the poles and/or the member being so shaped that the mean spacing between opposing surfaces of the pole and member varies in response to said movement whereby to vary the reluctance of the magnetic circuit.

In accordance with this invention the magnetic reluctance of the device is varied without substantially altering the cross-sectional area of the flux path.

The invention is of particular utility in transactors employed in protective relays in which the ratio of the secondary voltage to primary current may be varied by the movement referred to above.

In order that the invention may be fully understood a device having a laminated magnetic core and adjustable reluctance will now be described by way of example, with reference to an accompanying drawing in which:

FIG. 1 shows a cross-sectional view of the device having a movable member for adjusting the reluctance; and

FIG. 2 shows a circuit diagram of an adjustable transactor whose windings are wound on the laminated magnetic core in FIG. 1.

Referring now to the drawing a winding 8, having input terminals 9, is mounted on a shell-type laminated core 10 which has two magnetic pole pieces 11 and 12 defining between them a tapered air gap of rectangular cross section. A similarly tapered laminated member 13 is disposed transversely in the air gap, the member being internally threaded and mounted on an adjusting screw 14 which is in turn supported by limbs 15 and 16 of the core. The member 13 has two non-magnetic stops 17 and 18 arranged to prevent the member moving beyond desirable limits of movement; that is, beyond either side of

2

the air gap between the poles 11 and 12. A spring 19 between the limb 15 and the stop 17 is effective to urge the member 13 in a direction away from the head of the screw 14 to prevent undesirable movement of this member, when magnetised for example, due to "back-lash" in the adjusting screw threads.

A pointer 20 is arranged to be moved around a scale 21 in response to movement of the member 13 and is held against the stop 18 by a spring 22.

In operation, when the coil is energised, translational movement of the member 13 varies the length of the air gap and thereby the reluctance of the magnetic circuit, and the scale 21 may conveniently be calibrated so that it can exhibit predetermined settings of inductance possessed by the device.

It will be appreciated that the air gap may be anywhere within the magnetic circuit of the core and that the air gaps between the poles and the member may be any shape in cross-section, e.g. rectangular or part-annular, provided that the effective length of the air gap may be adjusted by limited relative movement between the member and the pole pieces 11 and 12 without substantially altering the effective cross-sectional area of the flux path between these two poles. Similarly, the magnetic core itself may be in any form defining a continuous magnetic circuit having one or more air gaps, for example, the core may be shaped substantially as a ring or the letter C.

As an example, one application of the device of FIGURE 1 is in the adjustable transactor of FIGURE 2 which includes a primary winding 23 energisable from a current source 24 and a secondary winding 25 connected to a load 26. The windings would be wound on the centre limb of the magnetic core 10 in a similar manner to that shown by the winding 8 in FIGURE 1. The secondary ampere-turns are arranged to be small compared with the magnetising (primary) ampere-turns so that when the primary winding 23 is energised a voltage output will be produced from the secondary winding 25 which is proportional to the current in the primary winding 23 but approximately 90° out of phase therewith. When the length of the gap is adjusted by the means provided, the ratio between the secondary volts and primary current may be varied. The scale may then be calibrated in terms of this ratio or in terms of the primary current for a specific output voltage.

What we claim as our invention and desire to secure by Letters Patent is:

1. An electromagnetic device comprising a magnetic core defining a closed magnetic circuit, said core having pole pieces with opposing surfaces spaced apart from one another, a winding carried by the core and energisable to cause the pole pieces to assume opposite polarities, a tapered elongate magnetic member mounted between the pole pieces with part of the member lying between the whole of said opposing surfaces of the pole pieces to define between said member and the pole pieces two air gaps one on each side of the major axis of said member, means for moving said member along its major axis to vary the length of the air gaps and thereby the reluctance of the magnetic circuit, and limit stops on said member for confining the movement thereof so that part of said member always lies between the whole of said opposing surfaces of the pole pieces, the said opposing surfaces of the pole pieces and the opposing surfaces of the member having the same shape and the same angle of taper whereby, for any position to which the said member is moved by said means, each air gap is of constant length over the

whole of the opposing surface of the respective said pole piece.

2. In a transactor, a device according to claim 1, including a primary winding and a secondary winding mounted on said core, a current supply means for energizing the primary winding to induce a voltage into the secondary winding, the secondary ampere-turns being small compared with the primary ampere-turns sufficient to insure that said voltage is proportional to said primary current at any width of said air gap, the said movement of the member being effective to vary the ratio between the secondary voltage and the primary current.

3. A device according to claim 1, including indicating means for indicating the position of said member relative to said pole pieces, said indicating means having a pivotally mounted element operatively connected to said member so that the angular position of said ele-

ment is dependent on the relative position of said member and said pole pieces.
